UNITED STATES PATENT OFFICE.

ERNEST E. PETERSON, OF CARSON LAKE, MINNESOTA.

ATTACHMENT FOR TRACK-LIFTING MACHINES.

Application filed September 8, 1924, Serial No. 736,533. Renewed January 14, 1926.

To all whom it may concern:

Be it known that I, ERNEST E. PETERSON, a citizen of the United States, residing at Carson Lake, in the county of St. Louis and 5 State of Minnesota, have invented new and useful Improvements in Attachments for Track-Lifting Machines, of which the following is a specification.

This invention relates to an attachment 10 for track lifting and throwing machines of the type wherein a car, adapted to be secured to the track to be moved, is provided with power driven mechanism for bodily raising the car, tracks, and ties, and for 15 shifting the same laterally.

The object of this invention is to provide in a machine of this kind simple and efficient means for controlling tilting movement of the car and tracks while the same are ele- 20 vated.

Heretofore, because of unequal distribution of weight between the rails, it has been difficult to control tilting during the lifting operation so that the lower ends of the 25 ties have had a tendency to dig into the ground and thus oppose or stop lateral movement of the mechanism. It is also practically impossible with the old types of such machines to maintain the ties in 30 horizontal position or at a predetermined slope while elevated, as is desirable in order to simplify tamping and grading the road bed. The present invention obviates these 35 difficulties and makes it possible to raise and carry the ties in horizontal position or at any desired angle.

This invention is particularly, although not exclusively, adapted to be applied to a machine of the type described and claimed 40 in United States Patent No. 1,264,376, dated April 30, 1918 granted to C. H. De Vey and Ernest E. Peterson.

In the accompanying drawings which illustrate the best form of this invention at 45 present known to me, Figure 1 is an end view of a car with my device mounted thereon; Fig. 2 is a plan view of the invention showing a fragmentary portion of the supporting car; Fig. 3 is an enlarged, trans- 50 verse section through the brake shafts; and Fig. 4 is a longitudinal, vertical section through the brake drums showing one of the supporting shafts partially in longitudinal section.

55 Referring to the drawings, I have used the numeral 5 to indicate a car having a

platform 6 adapted to support the lifting mechanism. This car is provided with suitable clamping hooks 7 adapted to engage the rails 8 which are secured to ties 9. 60 Mounted centrally on the car 5 is a thrust boom 10 provided at its base with a pedestal 11 adapted to be thrust downward against the surface of the ground between a pair of the ties 9. The boom 10 may be 65 actuated by any suitable mechanism such as the pinion 12 which meshes with a rack 13 indicated diagrammatically in Figs. 1 and 2. The shaft carrying the pinion 12 may be connected through suitable gearing, 70 such as that shown in the above mentioned Patent No. 1,264,376, with a motor (not shown) carried on the platform 6. A pin 14 pivotally connects the boom 10 and pedestal 11 so that when the said boom is 75 thrust downward to raise the car, tracks, and ties, the elevated mechanism may be swung laterally upon said pin.

To control or prevent tilting upon the pin 14 while the car and attached mechanism is being lifted, I provide cables or chains 15 and 16 which are severally connected at their lower ends to the lateral extremities of the pedestal 11. These cables extend substantially vertically from the 80 pedestal 11 and are severally wound upon shafts 17 and 18. The shaft 18 has a tubular form and encases a reduced portion of the shaft 17. Suitable journal bearings 19 support the ends of the shafts 17 and 18. 85 Severally fixed upon the shafts 17 and 18 near one side of the car are brake drums 20, provided on their peripheries with brake bands 21 adapted to be actuated by levers 22 and 23 respectively. One end of each 90 of the bands 21 is rigidly supported upon a bracket 24, while the opposite ends of said bands are attached to the levers 22 and 23, so as to be actuated thereby to apply or release the brakes.

To normally wind the cables 15 and 16 upon the shafts 17 and 18, spring actuated cables 25 are wound upon said shafts in a direction opposite to the winding of the cables 15 and 16. The cables 25 are maintained under tension by coiled springs 26, which are fixed at their lower ends on the 105 car frame.

Operation.

In operation, as the boom 10 is thrust 110 downward to raise the car and tracks, the

cables 15 and 16 are unwound from the shafts 17 and 18 and rotate said shafts to wind the cables 25 thereon against the action of the springs 26. When, as is usually the case, the loads upon the sides of the car are unequal, one side will have a tendency to rise first and to turn one of the shafts 17 or 18 before or faster than the other. Where the tilting of the car thus caused is undesirable, it may be prevented or limited by merely actuating one or the other of the brake levers 22 and 23. As will now be readily understood, when one of these levers is actuated, a brake will be applied so as to stop or retard rotation of the connected shaft. Thus, even where the load is very unequally distributed, the operator may cause the car to be raised horizontally or in any desired tilted position by proper manipulation of the levers 22 and 23. When the car and track is lowered by retracting the boom 10, the cables 15 and 16 will again be wound on the shafts 17 and 18 by the action of the cables 25 and springs 26.

Obviously, chains or other connecting means might be employed in place of the cables 15, 16 or 25 and any such substitution of means is considered within the spirit of my invention.

Having described my invention what I claim as new and desire to protect by Letters Patent is:

1. The combination with a railway car adapted to be attached to the supporting rails and provided with an independent support adapted to be engaged to raise the car and rails, of means severally connecting opposite side portions of said support with the sides of said car, and means for severally stopping or retarding the movement of said connecting means relative to said car while said car is raised on said support.

2. The combination with a railway car adapted to be clamped on the supporting rails and provided with a pedestal and a boom adapted to be engaged to raise the car and rails, of means severally connecting the sides of said pedestal with the sides of said car and means for severally retarding or stopping the movement of said connecting means relative to said car during the upward movement of said car on said boom

whereby lateral tilting of the car may be limited or prevented.

3. The combination with a railway car adapted to be secured to the supporting rails and provided with thrust means for simultaneously raising the car and rails, of independently revolute shafts on said car, flexible means severally connecting said shafts with opposite sides of said thrust means, and means for severally retarding or stopping rotation of said shafts.

4. The combination with a railway car adapted to be clamped on the supporting rails and provided with a pedestal and a boom adapted to be engaged to raise the car and rails, of independently revolute shafts on said car, flexible means severally connecting said shafts with opposite sides of said pedestal and means for severally retarding or stopping rotation of said shafts whereby lateral tilting of the car may be limited or prevented.

5. The combination with a railway car adapted to be secured to the supporting rails and provided with a pedestal and a boom pivotally joined to said pedestal and adapted to be engaged to raise the car and rails, of flexible means severally connecting the side portions of said pedestal with the side portions of said car, springs adapted to maintain said flexible means under tension, and means for severally retarding and stopping the movement of said connecting means relative to said car during the upward movement of said car on said boom whereby lateral tilting of the car on said pedestal may be limited or prevented.

6. The combination with a railway car adapted to be secured to the supporting rails and provided with thrust means for simultaneously raising the car and rails of independently revolute shafts on said car, flexible means arranged to be severally wound on said shafts and secured to with opposite side portions of said thrust means and brakes for severally retarding or stopping rotation of said shafts whereby tilting of the car relative to the thrust means may be controlled.

In testimony whereof, I have hereunto signed my name to this specification.

ERNEST E. PETERSON.
